United States Patent Office

Des. 221,091
Patented July 6, 1971

221,091

GAME BOARD

Frank C. Nowicki, 1144 Dionne, St. Paul, Minn. 55113

Filed Apr. 27, 1970, Ser. No. 22,643

Term of patent 14 years

Int. Cl. D21—01

U.S. Cl. D34—5

The figure is a view of the front face of the game board showing the embodiment of my new design.

The back of the game board is flat and unadorned.

I claim:

The ornamental design for a game board, as shown and described.
